(57) **CLAIM**

The ornamental design for a display screen or portion thereof with animated graphical user interface, as shown and described.

DESCRIPTION

FIG. 1 is a front view of a display screen or portion thereof with animated graphical user interface showing my new design.

FIG. 2 is a front view of a second image thereof;

FIG. 3 is a front view of a third image thereof;

FIG. 4 is a front view of a fourth image thereof;

FIG. 5 is a front view of a fifth image thereof;

FIG. 6 is a front view of a sixth image thereof; and,

FIG. 7 is a front view of a seventh image thereof.

The appearance of the animated graphical user interface sequentially transitions between the images shown in FIGS. 1 through 7. The process or period in which one image transitions to another image forms no part of the claimed design.

The outer broken lines in the drawings depict parts of the display screen or portion thereof that form no part of the claimed design. The other broken lines in the figures illustrate parts of the animated graphical user interface that form no part of the claimed design.
